US00D941867S

(12) **United States Design Patent** (10) Patent No.: **US D941,867 S**
Choi et al. (45) Date of Patent: ** Jan. 25, 2022

(54) **DISPLAY SCREEN WITH ANIMATED GRAPHICAL USER INTERFACE**

(71) Applicant: **LG Electronics Inc.**, Seoul (KR)

(72) Inventors: **Meeyeon Choi**, Seoul (KR); **Yoonshin Kim**, Seoul (KR); **Juhhyung Shin**, Seoul (KR); **Sol Eun**, Seoul (KR); **Byoungnam Lee**, Seoul (KR); **Eunjong Lee**, Seoul (KR)

(73) Assignee: **LG ELECTRONICS INC.**, Seoul (KR)

(**) Term: **15 Years**

(21) Appl. No.: **35/509,478**

(22) Filed: **Oct. 28, 2019**

(80) **Hague Agreement Data**

Int. Filing Date: **Oct. 28, 2019**

Int. Reg. No.: **DM/208199**

Int. Reg. Date: **Oct. 28, 2019**

Int. Reg. Pub. Date: **May 29, 2020**

(30) **Foreign Application Priority Data**

Apr. 29, 2019 (KR) 30-2019-0020286

(51) **LOC (13) Cl.** **14-04**

(52) **U.S. Cl.**

USPC **D14/486**; D14/490

(57) **CLAIM**

The ornamental design for a display screen with animated graphical user interface, as shown and described.

DESCRIPTION

1. Display screen with animated graphical user interface

1.1 : Front view 1

1.2 : Front view 2

1.3 : Front view 3

1.4 : Front view 4

1.5 : Front view 5

1.6 : Front view 6

1.7 : Front view 7

1.8 : Front view 8

1.9 : Front view 9

The broken lines depict portions of the display screen with animated graphical user interface that form no part of the claimed design. The appearance of the transitional image sequentially transitions between the images shown in reproductions 1.1-1.9. The process or period in which one image transitions to another image forms no part of the claimed design.

1 Claim, 9 Drawing Sheets
